UNITED STATES PATENT OFFICE.

THOMAS L. STURTEVANT AND THOMAS J. STURTEVANT, OF FRAMINGHAM, MASSACHUSETTS.

STEAM-GENERATOR.

SPECIFICATION forming part of Letters Patent No. 408,995, dated August 13, 1889.

Application filed November 12, 1888. Serial No. 290,570. (No model.)

To all whom it may concern:

Be it known that we, THOMAS L. STURTEVANT and THOMAS J. STURTEVANT, citizens of the United States, residing at Framingham, 5 in the county of Middlesex and State of Massachusetts, have invented certain new and useful Improvements in Steam-Generators; and we do hereby declare the following to be a full, clear, and exact description of the invention, such as will enable others skilled in the art to which it appertains to make and use the same, reference being had to the accompanying drawings, and to letters or figures of reference marked thereon, which form a part 15 of this specification.

This invention relates to steam-generators, and its aim is to produce a device which in its arrangement shall be extremely compact and yet provide a large amount of heating- 20 surface, and, furthermore, which shall reduce the danger from explosions, since the steam-generating parts are "sectional," so called.

The drawings accompanying this specification represent, in Figure 1, a sectional elevation diametrically and vertically of the generator. Fig. 2 is a horizontal cross-section on line $x x$ of Fig. 1.

In Fig. 1 of said drawings is represented a vertical steam-generator composed of a cylindrical outer shell A, within the lower middle portion of which is located a fire-pot B, and with an ash-chamber C below the latter. Said shell may be made of any suitable sheet metal; or, as in the present instance, it may be 35 a water-jacket, which extends down around the fire-pot, and is formed by two tubes—one inside the other—united at their opposite adjacent ends. The generator is surmounted by a solid disk or plate G, provided with a 40 central feed-opening for the admission of fuel. Contained within said shell or water-jacket A, and located above the fire-pot, is the steam-generating device D. Said device is composed of a series of concentrically-arranged 45 annular sections E, interconnected, as will be hereinafter described. Each of said steam-generating sections contains a chamber a. These in the present instance are formed of two tubes b c—one within the other. The adjacent ends of the tubes are then united to

create a sealed joint, and thus a closed generating-chamber is produced, while the inner tube is left open at both ends; hence the bore of each inner tube of every steam-generating section serves as a flue to transmit 55 the hot gases or other product of combustion from the fire-pot to the stack or flue F, which is secured in the plate G. In thus making steam-generating sections of the described form, and by disposing them concentrically 60 one within the other, a very compact steam-generator can be obtained, while its capacity is limited only by the number, size, or length of the several tubes which go to make up the individual generating-sections E, as likewise 65 the intensity of the fire. Further, the liability and danger from explosions are reduced, since the generating-chambers are interconnected, and are all made of the strongest possible form. When the said chambers 70 a a are capillary or contracted, the several sections E are united in series by the pipes d d. The latter are so disposed that the water-supply is compelled to take a circuitous course, as shown—that is, the discharge and 75 supply pipes in each section of the series are located at opposite ends. Thus in Fig. 1 the water-supply pipe e enters at the top of the generating-chamber in the outermost section. The discharge-pipe d therefrom is located at 80 the lower opposite portion, and connects with the corresponding part of the next adjacent section located interiorly thereof. The discharge or outlet pipe d of this latter section, however, is at the top; hence water forced 85 in proper quantities within the chamber of the outer section is compelled to pass successively through each generating-chamber until when it reaches the chamber of the center section it has assumed the form of dry, 90 highly-heated steam. Thence it passes by the main discharge-pipe f to the engine or other source to be supplied.

What we desire to claim is—

1. A steam-generator composed of a number 95 of steam-generating sections connected in series, each section being composed of two tubes—one within the other—with their adjacent ends united to form a closed steam-chamber, interconnecting pipes at the oppo- 100

site extremities of the sections which unite the adjacent sections, and a common fluid-supply and steam-discharge, all substantially as herein set forth and described.

5. 2. In combination with a suitable shell, its fire-pot, co-operating flue, and ash-chamber, an interconnected series of concentrically-arranged steam -generating sections within said shell and the common fluid-supply and steam-discharge, each section being composed of two tubes contiguous at various points—one within the other—the adjacent ends being united to form a closed annular chamber therebetween and having a supply and discharge at opposite ends, substantially as herein specified.

3. In combination with an inclosing-shell or water-jacket, a fire-pot B, with its co-operating flue F, the steam-generators E, arranged 20 in sections which are connected in series united by tubes d d to insure water-circulation, each section being composed of two

tubes b c—one within the other, and fastened together at their adjacent ends, the interior periphery of one and the exterior periphery 25 of the other non-contiguous—and a common fluid-supply e and steam-discharge f, substantially as and for purposes herein set forth.

4. In a steam-generator, the combination, with a fire-pot B and its flue F, of the series 30 of steam-generating sections E, arranged in sections which are connected in series, constructed and united as set forth, the water-jacket A, which incloses said sections and fire-pot, and a common fluid-supply e and 35 steam-discharge f, substantially as stated.

In testimony whereof we affix our signatures in presence of two witnesses.

THOMAS L. STURTEVANT.
THOMAS J. STURTEVANT.
